MANUFACTURE OF CHENILLE YARN

Filed Nov. 22, 1939

UNITED STATES PATENT OFFICE

2,203,561

MANUFACTURE OF CHENILLE YARN

Reuben Broder, New York, N. Y., assignor to
Zenith Textile Corporation, New York, N. Y.,
a corporation of New York

Application November 22, 1939, Serial No. 305,589

7 Claims. (Cl. 28—62)

This invention relates to the manufacture of round-section chenille yarn from chenille yarn having radial tufts.

An object of this invention is to provide an improved method and means for curling the radially positioned threads of chenille yarn by first mechanically compacting the threads into a curled form of much smaller diameter, and then subjecting the round chenille to an ironing treatment while undergoing a feeding movement through a heated tube.

Another object of this invention is to provide means for continuously imparting a partially compacted and spirally curled form to a chenille yarn, comprising an elongated tube having a conical inlet end and having a conical thread in said inlet end, the said elongated tube having an inner diameter corresponding to the smallest diameter of the conical inlet, and in providing means for heating the said tube and means for rotating the heated tube.

Another object of this invention is to provide means for frictionally restraining and tensioning chenille yarn against rotation at the entrance into said conical inlet and in providing means for pull-feeding the chenille yarn at the exit end of the said tube, the said tensioning and feeding means being in alignment with the axis of said tube.

Another object of this invention is to cause the pull-feed to be rotated at such a speed as to pull through the tube a length of curled yarn exactly corresponding to the length of yarn being curled by the threaded tube.

With the above and other objects in view, the invention will be hereinafter more particularly described, and the combination and arrangement of parts will be shown in the accompanying drawing and pointed out in the claims which form part of this specification.

Reference will now be had to the drawing, wherein like numerals of reference designate corresponding parts throughout the several views, in which:

Figure 1 is an end view of chenille yarn before treatment.

Figure 2 is an end view of the chenille yarn after treatment, the figure being on an enlarged scale.

Figure 3 is a side elevation of apparatus for carrying out my method of treatment of the chenille.

Figure 4 is a central cross-sectional view of the apparatus shown in Figure 3.

Figure 5 is a cross-sectional view of a modified

tube having a portion of its length threaded, the thread being a continuation of the thread in the conical inlet to the tube.

In the illustrated embodiment of the invention, the numeral 10 indicates an elongated tube having an integral conical inlet 11. The inlet 11 has a conical thread 12 throughout its length.

The tube 10 has been rotatably mounted in ball bearings 13 carried in bearing supports 14. A pulley 15 fixed to the tube 10 is driven by a belt 16 and causes rotation of the tube.

The rotatably mounted tube 10 is enclosed by a stationary electrical heating unit 17 having a high-resistance wire 18. An electric current passing through the high-resistance wire causes the wire to get hot and to heat the heating unit 17 and the tube 10.

The bearing supports 14 and the heating unit 17 may be secured to a base 19. Secured to the base are spaced supports 20 having eyelets 21 in alignment with the axis of the tube 10.

Secured to the base at the outlet end of the tube 10 is a bearing 22 having a shaft 23 rotatably mounted therein. A roller 24 has been fixed to the shaft 23. Supported by an extension 25 of the bearing 22 is a carrier 26 having an elongated vertical slot 27. A roller 28 has an integral axle 29 journaled in the slot 27 and is thus adapted for vertical motion to and from the roller 24.

A gear 30 fixed to the shaft 23 and driven in any suitable manner in direction of the arrow, causes rotation of the roller 24 and the superposed roller 28.

As shown in Figure 1, the chenille yarn 31 to be treated has a central core of binding threads 32 interlocked by twisting with more or less radial threads 33, the ends of the threads 33 being exposed. The yarn 31 is passed through eyelets 21, 21 having a small internal diameter whereby the yarn 31 is frictionally restrained and tensioned against rotation, while permitting motion therethrough.

The yarn 31 after being passed through the eyelets is pulled through the conical inlet 11 and out of the tube 10 and around the rollers 24 and 28. The roller 28 has considerable weight and causes a frictional drag to be exerted on the yarn passing therebetween. When the gear 30 rotates the shaft 23 and the attached roller 24, a pull-feeding action takes place and the yarn is continuously conveyed through the entire length of the tubular portions 11 and 10.

When the yarn 31 enters into the conical inlet 11, the conical screw thread 12 comes into engagement with the radial threads 33 and gradu-

- ally curls the said threads in spiral form and compresses them to a much smaller diameter corresponding to the internal diameter of the tube 10. The partially compacted and curled 5 yarn in passing through the heated portion of the tube 10 is ironed and assumes a permanent set and so that the chenille yarn in the said form 34 is of the same diameter throughout and has finely curled threads.
- 10 It is to be noted that the rotation of the threaded tube 10 must be in the direction of the twisting of the core 32 of the chenille yarn 31.
- The temperature of the heating unit 17 is regulated to suit the particular yarn worked upon.
- 15 It is essential that the pull-feeding mechanism shall be geared to pull through the tube a length of curled chenille yarn exactly corresponding to the length of tufted chenille being curled and fed by the screw threaded conical inlet 11.
- 20 In accordance with the patent statutes I have described and illustrated the preferred embodiments of my invention, but it will be understood that various changes and modifications can be made therein without departing from the spirit 25 of the invention as defined by the appended claims.

I may utilize the modified heating or ironing tube shown in Figure 5, the said tube having an internal screw thread 35 for a portion of its length and forming a continuation of the thread in the conical inlet to the tube.

I claim:

1. Means for continuously imparting a compacted round-section form to a chenille yarn having radial tufts, comprising an elongated tube having a conical inlet end and having a conical thread in said inlet end, said elongated tube having an inner diameter corresponding to the smallest diameter of said conical inlet, means in front of said inlet for frictionally restraining and tensioning chenille yarn, means for heating said tube, means for rotating said heated tube to cause said conical thread to forcibly curl said chenille yarn into a substantially solidly compacted mass of round-section and of considerably smaller diameter, and means for feeding said curled chenille yarn through said tube in timed relation with the time required to heat and set said curled chenille yarn.
2. Means for continuously imparting a compacted curled form to a chenille yarn having radial tufts, comprising an elongated tube having a conical inlet end and having a conical thread in said inlet end, said elongated tube having an inner diameter corresponding to the smallest diameter of said conical inlet, means in front of said inlet for frictionally restraining and tensioning chenille yarn against rotation, means for heating said tube, means for rotating said heated tube to cause said conical thread to forcibly curl said chenille yarn into a substantially solidly compacted mass of considerably smaller diameter, and means for pull-feeding said curled chenille yarn through said tube in timed relation with the time required to heat and set said curled chenille yarn, said tube being adapted to permit motion therethrough of chenille yarn being curled solely in the direction of the winding of said thread.
3. Means for continuously imparting a compacted curled form to a chenille yarn having radial tufts, comprising an elongated tube having a conical inlet end and having a conical thread in said inlet end, said elongated tube having an inner diameter corresponding to the smallest diameter of said conical inlet and being threaded

for a portion of its length, means in front of said inlet for frictionally restraining and tensioning chenille yarn against rotation, means for heating said tube, means for rotating said heated tube to cause said conical thread to forcibly curl said chenille yarn into a substantially solidly compacted mass of considerably smaller diameter, and means for pull-feeding said curled chenille yarn through said tube in timed relation with the time required to heat and set said curled chenille yarn, said tube being adapted to permit motion therethrough of chenille yarn being curled solely in the direction of the winding of said thread.

4. Means for continuously imparting a compacted curled form to a chenille yarn having radial tufts, comprising an elongated tube having a conical inlet end and having a conical thread in said inlet end, said elongated tube having an inner diameter corresponding to the smallest diameter of said conical inlet and being threaded for a portion of its length, said tube thread forming a continuation of said conical thread, means in front of said inlet for frictionally restraining and tensioning chenille yarn against rotation, means for heating said tube, means for rotating said heated tube to cause said conical thread to forcibly curl said chenille yarn into a compacted mass of considerably smaller diameter, and means for pull-feeding said yarn through said tube in timed relation with the time required to heat and set said yarn having radial tufts into curled chenille yarn, said threaded tube being adapted to permit motion therethrough of chenille yarn being curled solely in the direction of the winding of said thread.

5. The combination, in a machine for continuously imparting a partially compacted and spirally curled form to a chenille yarn having radial tufts, comprising an elongated tube having a conical inlet end and having a conical thread in said inlet end, said elongated tube having an inner diameter corresponding to the smallest diameter of said conical inlet and being threaded for a portion of its length, said tube thread forming a continuation of said conical thread, means in front of said inlet for frictionally restraining and tensioning chenille yarn against rotation, means for heating said tube, means for rotating said heated tube to cause said conical thread to forcibly curl said chenille yarn into a partially compacted mass of considerably smaller diameter, and means for pull-feeding said yarn through said tube in timed relation with the time required to heat and set said yarn having radial tufts into curled chenille yarn, said threaded tube being adapted to permit motion therethrough of chenille yarn being curled solely in the direction of the winding of said thread.

6. The combination, in a machine for continuously imparting a partially compacted curled form to a chenille yarn having radially tufted elements by spirally twisting said tufted elements while heated, comprising an elongated tube having a conical inlet end and having a conical thread in said inlet end, said elongated tube having an inner diameter corresponding to the smallest diameter of said conical inlet and being threaded for a portion of its length, means in front of said inlet for frictionally restraining and tensioning chenille yarn against rotation, means for heating said tube, means for rotating said heated tube to cause said conical thread to forcibly curl said chenille yarn into a partially compacted mass of considerably smaller diameter, and means for pull-feeding said yarn through

said tube in timed relation with the time required to heat and set said yarn, said threaded tube being adapted to permit motion therethrough of chenille yarn being curled and heat treated solely in the direction of the winding of said thread.

7. The combination, in a machine for continuously imparting a partially compacted curled form to a chenille yarn having radially extending threads by spirally threading said radial threads while heated to form a uniformly curled yarn of constant cross-section and having finely curled threads, comprising an elongated tube having a conical inlet end and having a conical screw thread in said inlet end, said elongated tube having an inner diameter corresponding to the small-

est diameter of said conical inlet and being threaded for a portion of its length, means in front of said inlet for frictionally restraining and tensioning chenille yarn against rotation, means for heating said tube, means for rotating said heated tube to cause said conical thread to forcibly curl said chenille yarn into a partially compacted mass of considerably smaller diameter, and means for pull-feeding said yarn through said tube in timed relation with the time required to heat and set said yarn, said rotating screw threaded tube being adapted to permit motion therethrough of chenille yarn being curled and heat treated solely in the direction of the winding of said thread.
